DRYING DEVICE FOR BAR SOAP

Raimond Johannes Mättik, Linkoping, Sweden

Application November 20, 1950, Serial No. 196,633

3 Claims. (Cl. 45—28)

1

This invention relates to a drying device for bar soap.

When using bar soap for washing and thereafter placing said soap on a soap dish, lather will be smeared on said soap dish. This disadvantage will be overcome by using the drying device according to the present invention, which device includes a casing having an inlet opening for the bar of soap just used, a vane wheel under the inlet opening with a number of vanes thereon arranged radially in parallel planes, an outlet opening in the casing under the vane wheel for the bar of soap, and a closure or door normally covering the outlet. This door is interconnected with the vane wheel in such a manner that, in the neutral position of said door, a stop on the door permits the vane wheel to turn to a position in which one of the vanes on the vane wheel will be approximately horizontal, so that said vane will constitute a support for the bar of soap. However, upon displacement of the door, when taking a bar of soap out of the drying device, the stop will also be displaced so that a bar of soap that may be placed on the vane wheel will, by turning the vane wheel one quarter revolution, be released to fall down to the outlet in the casing.

According to a further embodiment of the invention, the device has an inlet opening in the casing for the bar of soap just used; under this inlet opening a vane wheel with a number of vanes thereon arranged radially in parallel planes, and under said vane wheel an outlet opening for the soap and a door normally covering the inlet opening. This door is interconnected with the vane wheel in such a manner that, in the neutral position of said door, a stop on the door permits the vane wheel to turn to a position in which one of the rods 6 thereon will be approximately horizontal, so that said vane will constitute a support for the bar of soap. Then, upon the displacement of the door during the insertion of a bar of soap into the drying device, the stop will also be displaced so that a bar of soap which may be placed on the vane wheel will, by a partial turning of the vane wheel one step, be released to fall down to the outlet opening.

In drawings, which illustrate two embodiments of the invention,

Fig. 1 is a front view of an embodiment of a drying device according to the invention;

Fig. 2 is a sectional view taken on the line A—A in Fig. 1; and

Fig. 3 is a corresponding sectional view of an-

2

other embodiment of the drying device according to the invention.

The embodiment of the drying device shown in Figures 1 and 2 includes a casing comprised by two side plates 4, which are held together by cross bars 2. A grid 3, attached to said cross bars, is comprised by vertically positioned metal rods, said rods being at their bottom ends bent in the forward direction, so that they form a basket 4, which basket forms the bottom of an outlet opening for the bar of soap. A vane wheel is carried in bearings which rotatably mount a shaft 5, said shaft being supported through the bearings by the side plates 4. This vane wheel is comprised by a series of four rods 6 radially positioned around the shaft 5. Further, between said plates, a closure or door 7 is mounted by bearings which support a shaft 8, this door normally covering the outlet opening.

As shown in detail in Fig. 1, each of the vanes on the vane wheel is comprised by a number of radially positioned rods. A cover 10 encloses the vane wheel, this cover having a downwardly bent top portion comprised by a number of approximately vertically arranged bars 11, which are positioned radially in parallel planes along the shaft 5 of the vane wheel and which are situated between the rods 9 on the vane wheel. The bottom portion of said cover is bent towards the vane wheel into an approximately horizontal position. Also, said portion is comprised by rods 21 arranged in the same radial planes as the bars 11.

35 A pin 12 is so positioned on the door 7 that the outer ends 13 of the rods on the vane wheel, that is, those situated to the extreme right (Fig. 1) are arranged at one end of the vane wheel in such a manner that the ends of the rods will contact said pin and thus prevent turning of the vane wheel.

40 The drying device described above and shown in Figures 1 and 2 in operation functions in the following way: let it be assumed that a bar of soap is placed in the basket 4 and another bar of soap on the horizontal rods of the vane wheel positioned towards the grid 3. If one wants to take a bar of soap out of the drying device one at first has to swing the closure or door 7 inwardly and upwardly so that one will be able to take the bar of soap from the basket 4. In doing so the door will be swung inwardly so far that the pin 12 moves to a position in front of the middle portion 25 of said rod 6, which is inwardly offset from the right outer end 13, as shown in Fig. 1. The bar of soap resting on said

horizontal rods will now on account of its weight partially turn the vane wheel in a counter-clockwise direction, as shown in Fig. 2. However, after turning through a slight angle, the horizontal portion 25 of said rod 6 will contact a circular guide rib 14 on the door. This will for a short while prevent continued turning of the vane wheel. One may take the bar of soap resting in the basket 4 and use same. Upon removing the hand from the basket 4 the door 7, on account of its weight, will swing in the counter-clockwise direction (Fig. 2). However, on account of its inertia, the door will swing somewhat outwardly past its vertical position, as shown on the drawing. Thus the outer end 13 of the rod 6 is released and the bar of soap resting on the vane wheel now will be able to turn the wheel a quarter of a revolution. The soap thereby falls downwardly into the basket 4. When the bar of soap, which was taken out of the drying device, has been used, one has to insert the bar of soap into the drying device through the inlet opening between the grid 3 and the bars 11.

The function of the bars 21, referred to above, is to remove a bar of soap which has been dried on the vane wheel.

Reference numeral 22 designates a stop for preventing reverse turning of the vane wheel.

A further embodiment of the drying device is shown in Fig. 3. The outlet opening for bars of soap from this device is not covered by a door. Instead the device has a closure or door 24 normally covering the inlet opening, said door being swingably carried in bearings which mount a shaft 23 extending between the side plates 1. A latch 15 is swingably carried by a pivot just above the vane wheel. The function of this latch is to contact axially extending pins 16 arranged on the rods 6 of the vane wheel. Between the door 24 and the latch 15 there is a link 17 which transmits movement to the vane wheel. A spring 18 is arranged to bias the latch to swing to the position shown in the drawing, in which position the latch is in the path of one of said pins 16.

The drying device shown in Fig. 3 functions as follows: Normally a bar of soap rests in the basket 4 and another bar of soap on the horizontal rods 6 of the vane wheel situated near the grid 10. When one desires to wash oneself one takes the bar of soap resting in the basket 4 and uses it. After use, the bar of soap is placed on the closure or door 24. Thereby the door will be pressed downward. The motion of said door is now transmitted to the latch 15 through the link 17 thereby swinging said latch in a clockwise direction (Fig. 3) so that the pin 16 engaged thereby will be released. The bar of soap resting on the vane wheel now turns the wheel a quarter of a revolution on account of its weight, and the soap falls down into the basket 4. At the end of the swinging movement of the door 24, the bar of soap resting on the door will fall down on the vane wheel. A portion of the latch is formed with a rounded edge 19 as a cam surface, so arranged that it will be in the

path of movement of the pins 16, when the latch is swung out of the engaging position. After the vane wheel has been turned through a quarter of a revolution, the next pin 16 will contact said cam surface. When the door 24 is released, the spring 18 will return the latch 15, whereby the pin 16 resting on the cam surface 19 is able to be moved slightly in a clockwise direction against a stop lug 20 on the latch. Thus there is now a bar of soap resting on the vane wheel and another bar of soap in the basket 4.

One advantage of the drying device according to the invention is the fact that one is obliged to use two bars of soap simultaneously, of which one bar is always in the drying device for drying. Therefore, the drying time for each bar of soap will be twice as long as by the method hitherto used.

What I claim is:

- 20 1. In a dispenser for bar soap, a casing having an opening therein, a pivotally mounted closure normally closing said opening, a wheel rotatably mounted in said casing and adapted to support at least one bar of soap, and means forming a connection between said pivotally mounted closure and said wheel whereby swinging movement of said pivotally mounted closure will cause said wheel to deposit a bar of soap on the bottom of the casing adjacent the opening in the latter.
- 25 2. In a dispenser for bar soap, a casing having an opening therein, a wheel rotatably mounted in said casing and having radially disposed projections thereon adapted to support a bar of soap, and a closure for said opening pivotally mounted in the casing and having a stop thereon adapted to abut one of the radially disposed projections on the wheel to prevent rotation of the latter when the closure is swung to open position.
- 30 3. In a dispenser for dispensing dry bars of soap, a casing having spaced apart inlet and outlet openings therein through which bars of soap may be inserted and removed respectively, a wheel rotatably mounted in the casing and having radially disposed projections thereon adapted alternatively to support a bar of soap, a closure pivotally mounted adjacent said outlet opening, a stop on said closure mounted in the path of movement of the projections on the wheel and abutting projections on the wheel to prevent partial rotation of the latter when the closure is swung in open position, and adapted to be abutted by other arcuately spaced projections on the wheel to permit the wheel to partially rotate to deposit a bar of soap on the bottom of the casing adjacent the outlet opening as the closure is swung to closed position.
